UNITED STATES PATENT OFFICE.

SCOTT STEWART, OF RIVESVILLE, WEST VIRGINIA.

SHADE HOLDING APPARATUS.

1,188,698.

Specification of Letters Patent. Patented June 27, 1916.

Application filed November 18, 1915. Serial No. 62,182.

To all whom it may concern:

Be it known that I, SCOTT STEWART, a citizen of the United States, residing at Rivesville, in the county of Marion and State of West Virginia, have invented certain new and useful Improvements in Shade-Holding Apparatus, of which the following is a specification.

My invention relates to improvements in means for adjusting window shades and holding them in adjustment in desired positions.

An important object of the invention is to provide means of the above mentioned character, which will permit of the free up and down adjustment of the shade, and will hold the same in the desired adjusted position, against undue lateral movement.

A further object of the invention is to provide means of the above mentioned character, which are extremely simple in construction, inexpensive to manufacture, and convenient in use.

Other objects and advantages of the invention will be apparent during the course of the following description.

In the accompanying drawings forming a part of this specification and in which like numerals are employed to designate like parts throughout the same, Figure 1 is a side elevation of apparatus embodying the invention, parts being shown in section, Fig. 2 is a vertically longitudinal sectional view taken on line 2—2 of Fig. 1, Fig. 3 is a perspective view of a cord holding member, secured to the lower sash frame, Fig. 4 is a side elevation with parts removed, of a detachable clamp, carried by the shade, Fig. 5 is a sectional view taken on line 5—5 of Fig. 4, Fig. 6 is a side elevation, parts omitted, of a different form of cord clamp, and, Fig. 7 is an enlarged horizontal section taken on line 7—7 of Fig. 6.

In the drawings, wherein for the purpose of illustration is shown a preferred embodiment of my invention, the numeral 10 designates a window frame of any well known or preferred construction, within which is mounted upper and lower vertically movable sash frames 11 and 12. These sash frames have connection with cords 13, passed about pulleys 14, carrying weights 15, as is customary.

Secured to the top of the window frame 10 is a depending bracket 16, carrying a pulley 17, engaged by a cord or flexible ele-

ment 18. This cord extends laterally about a pulley 19 and carries a weight 20. The lower end of the cord 18 carries a ball 21, and this end of the cord is adapted for insertion within an opening or slit 22, in a cord holding bracket or device 23, having a base 24, secured to the lower end of the lower sash frame 12, by means of screws 25 or the like. The function of the weight 20 and associated elements is to retain the cord 18 taut, when the lower sash frame 12 is raised and lowered.

The numeral 26 designates a curtain, the lower end of which is secured to the usual stick 27. This curtain is attached to a cylinder or roll 28, provided with the usual spring means for rotating it in one direction to wind the curtain thereon, but the ordinary pawl and ratchet means to hold the cylinder 75 against rotation is omitted, the cylinder being provided at its ends with pins 29, rotatably mounted within apertures in brackets 30, attached to the upper end of the upper sash frame 11.

A detachable clamp, designated as a whole by the numeral 31, is secured to the stick 27, for engaging with the cord 18, whereby the lower end of the curtain may be connected with this cord. This detachable 85 clamp, as more clearly shown in Figs. 4 and 5, comprises a U-shaped body portion 32 receiving the stick 27 and attached thereto by means of pins 33 or the like. Pivoted upon this body portion 32 by means of pins 34, is 90 a pair of jaws 39. The inner ends of these jaws are pivotally connected by a link 40, whereby they move together. The cord 18 is adapted to pass between these jaws and to be engaged thereby. The jaws carry 95 downwardly extending fingers 41 having shoulders 42. These shoulders are engaged by a curved leaf spring 43, tending to move the jaws inwardly toward each other. The leaf spring 43 is held against lateral movement by a plate 44, rigidly attached to the body portion 32 by means of pins 45 or the like.

It is obvious that by moving the fingers 41 toward each other, the jaws 39 will move 105 apart, and release the cord 18, thus permitting the curtain to be raised and lowered and when the fingers 41 are released, the spring 43 will automatically swing these jaws inwardly, whereby they 110 have clamping engagement with the cord to hold the curtain against movement.

In Figs. 6 and 7, I have shown a slightly different form of cord clamping means, the same comprising jaws 46, pivoted to the body portion 32, as shown at 47. These 5 jaws have grooves 48 to receive the cord 18 and have interfitting extensions 49, pivotally connected by means of a pin 50. The jaws 46 carry outwardly extending fingers 51, connected by cords of flexible elements 10 52, as shown. A spring 53 engages shoulders 54 upon the jaws 46, and tends to swing them inwardly. A plate 55 is attached to the body portion 32 and prevents lateral movement of the spring. 15 In operation, it is obvious that, when the lower sash frame 12 is raised and lowered, the cord 18 will move with it, the weight 20 and associated elements retaining it taut. This movement of the cord 20 will of course move the shade 26 but the same may be again conveniently adjusted by manipulation of the clamp 31. When the upper sash frame 11 is moved upwardly, the curtain will unwind and when it is 25 moved downwardly the curtain will wind upon the cylinder 28. The curtain may be moved up and down independently of the sash frame or frames.

It is to be understood that the form of 30 my invention herewith shown and described is to be taken as a preferred example of the same, and that various changes in the shape, size, and arrangement of parts may be resorted to without departing from 35 the spirit of the invention or the scope of the subjoined claims.

Having thus described the invention, I claim:—

1. The combination with a window 40 frame and a vertically movable sash frame arranged therein, of a flexible element connected with the vertically movable sash frame for movement therewith, automatic means to take up the slack in the flexible

element upon the upward movement of the 45 sash frame whereby the flexible element is retained taut, a self-winding shade arranged near the window frame, and means for connecting the shade with the flexible element.

2. The combination with a window 50 frame and a vertically movable sash frame arranged therein, of a flexible element arranged near the central portion of the sash frame and extending longitudinally thereof and connected with the lower portion 55 of the sash frame to be moved thereby, automatic means to take up the slack in the flexible element upon the upward movement of the sash frame whereby the flexible element is retained taut, a self-winding 60 shade arranged near the upper portion of the window frame, and a device secured to the shade and adapted to have detachable clamping action with the flexible element whereby the shade may be held against 65 movement with relation to the flexible element.

3. The combination with a window frame and a vertically movable sash frame arranged therein, of a pulley connected with 70 the upper portion of the window frame, a flexible element passed about the pulley, a weight connected with one end of the flexible element, a lift element secured to the lower end of the sash frame and having a 75 slot to receive the lower end of the flexible element, a self-winding shade arranged near the window frame, and a clamping device carried by the shade and embodying a pair of oppositely arranged jaws to receive 80 the flexible element therebetween.

In testimony whereof I affix my signature in presence of two witnesses.

SCOTT STEWART.
